DESIGN FOR A TOY FIGURE

Bonnie Young, New York, N. Y., assignor to J. Swedlin, Inc., New York, N. Y., a corporation of New York

Application May 26, 1938, Serial No. 77,412

Term of patent 7 years

To all whom it may concern:

Be it known that I, Bonnie Young, a citizen of the United States, residing in New York city, in the county and State of New York, have invented a new, original, and ornamental Design for a Toy Figure, of which the following is a specification, reference being had to the accompanying drawing, forming part thereof.

Fig. 1 is a perspective view of a toy figure, showing my new design.

Fig. 2 is a side view thereof on a reduced scale. The characteristic feature of the design resides in the grotesque appearance of the face and ears.

I claim:

The ornamental design for a toy figure, substantially as shown and described.

BONNIE YOUNG.
